UNITED STATES PATENT OFFICE

SAMUEL WACHSMAN, OF NEW YORK, N. Y.

LIQUID CONTAINER

Application filed February 18, 1930. Serial No. 429,446.

This invention relates to liquid containers, and particularly to an improved container adapted to dispense a disinfecting liquid in small quantities.

5 Another object is to provide an improved container adapted to dispense liquids, the structure being such that the liquid cannot flow from the container until disturbed by an absorbing member inserted into the discharge opening to permit the entrance of a 10 replacing quantity of air.

A further object, more specifically, is to provide a container having a discharge opening near the bottom with the neck and stopper 15 formed to act not only as a stopper but as a discharge opening and an overflow cup.

In the accompanying drawings,—

Figure 1 is a sectional view through Figure 2 through a liquid container disclosing an 20 embodiment of the invention, the section being taken on the line 1—1 of Figure 2;

Figure 2 is a front view of the container shown in Figure 1;

Figure 3 is a front view of the stopper 25 shown in Figure 1.

Referring to the accompanying drawings by numerals, 1 indicates a base which is preferably formed integral with the respective sides 2. The device may be made triangular- 30 shaped or square, but is preferably arranged with the sides 2 tapering upwardly substantially to point 3. One of the sides is provided with a neck 4 preferably integral with the side extending normal to the wall 2 so as 35 to be at an angle to the horizontal.

As shown on the drawings, the device is made from glass and in one piece, except for the stopper 5, but if preferred, the device may be made of other material, and also may be 40 made from a number of pieces secured properly together so as to receive and retain the liquid 6. The neck 4 extends outwardly a desired distance and is preferably provided with an enlargement or bead 7 against which 45 the flange 8 of stopper 5 rests. The bore of the neck 4 extends through wall 2 into the container, except for the flange or extension 9 projecting a short distance downwardly from the upper part of the neck but in line 50 with one of the walls 2. This leaves a com-

paratively large opening 10, so far as the neck 4 is concerned, but this neck is normally closed by the bottom plate 11 of stopper 5, except for the discharge opening 12 arranged in plate 11. Opening 12 is small 55 compared to the diameter of the stopper, so that normally when the level of the liquid 6 is as shown in Figure 1, only a very small quantity or part of the liquid will be in the opening 12, as illustrated in Figure 1. Occasionally there may be an overflow of liquid by reason of the expansion of air in the upper part of the container, and when this is the case the overflowing liquid discharges into the stopper. Usually this discharge never exceeds the lining 13, and consequently, this overflow may be used by the dentist or other person using the device. Ordinarily, the liquid in the container is removed by absorption which occurs when a person inserts a 60 small quantity of cotton into the aperture in the stopper. If an appreciable quantity of liquid is absorbed, a small bubble of air will be allowed to enter and pass to the upper part of the container, so that there will always be liquid in opening 12. The container 65 is intended to fit rather snugly in the neck 4, but may be readily removed or rotated. During office hours in a dental office the parts are left substantially as shown in Figure 1, but when the device is not in use stopper 5 is 70 rotated until opening 12 comes opposite the flange or projection 9. This will substantially seal the respective parts so that no dust can enter and also so that there will be 75 practically no evaporation of the alcohol or other liquid. When it is desired to fill the container stopper 5 is removed and the container may be quickly and easily filled by 80 reason of the large opening 10. It is, of course, understood that when filling the container the opening 10 will be at the highest point. After the container has been filled stopper 5 is replaced and then the container 85 may be positioned on a support, as illustrated in Figure 1.

Preferably the container is to be manufactured in the shape of a pyramid because this shape permits the container to receive a maximum quantity of liquid and a minimum 90

quantity of air and at the same time function as described.

What I claim is:—

1. A liquid container, comprising a body having a discharge opening near the bottom, a neck surrounding said discharge opening and extending at an angle to the horizontal, a depending flange at the upper part of the discharge opening acting to partly close said opening, a rotatable hollow stopper positioned in said neck and formed with a discharge aperture in the bottom thereof, said aperture being located at one side of said bottom, so that when the stopper is in one position liquid may flow into and through the aperture and when moved to the opposite position will be covered by said flange, so that no liquid can flow from said container, the upper part of said stopper acting as a dipping compartment when said aperture in said bottom is in alignment with said opening.
2. A liquid container, comprising a glass body having a base and side walls tapering to a point, one of said side walls having a discharge opening adjacent said base, a neck surrounding said discharge opening and extending at an angle to the bottom of said body, and a rotatable hollow stopper being open at one end and positioned in said neck, said stopper having a bottom plate at the opposite end formed with an aperture near one edge whereby part of the stopper will act as a dipping compartment when said aperture is in alignment with said discharge opening.
3. A liquid container comprising a body having a discharge opening adjacent the bottom in one of the side walls thereof, a tubular neck extending from the wall having said opening, said neck surrounding said opening, said wall being formed with a flange partly closing said opening, said neck extending at an angle to the horizontal so that the outer end of the neck will be at a higher level than the inner end, and a hollow stopper rotatably mounted in said neck, said stopper being open at one end and at the opposite end having a bottom plate formed with an aperture therein and appreciably smaller than said discharge opening and located near the periphery of said bottom plate, said stopper conforming to the shape of said neck whereby the part of the stopper adjacent said aperture acts as a dipping compartment when the aperture in the stopper is in registry with said opening, said stopper being capable of rotation so that when the aperture in said bottom plate is moved to a point opposite said flange, said opening will be closed.
4. Signed at New York, in the county of New York and State of New York, this 13th day of February, A. D. 1930.

SAMUEL WACHSMAN.
